DESIGN FOR A SPRAY GUN OR SIMILAR ARTICLE

Everett Worthington, Scarsdale, N. Y., assignor to American Can Company, New York, N. Y., a corporation of New Jersey

Application July 14, 1938, Serial No. 78,484

Term of patent 14 years

To the Commissioner of Patents:

Be it known that I, Everett Worthington, a citizen of the United States, residing at 15 Oak Lane, village of Scarsdale, county of Westchester, and State of New York, have invented a new, original, and ornamental Design for a Spray Gun or Similar Article, of which the following is a specification, reference being had to the accompanying drawing, forming a part thereof.

The figure is a perspective view of a spray gun or similar article, showing my new design.

The opposite side of the spray gun is substantially like the side shown. The dominant features of my design reside in the portions shown in full lines.

I claim:

The ornamental design for a spray gun or similar article, as shown and described.

EVERETT WORTHINGTON.
